UNITED STATES PATENT OFFICE.

JAMES F. MAYS, OF LEXINGTON, NORTH CAROLINA, ASSIGNOR TO MAYS ACCOUNTING MACHINE COMPANY, OF LEXINGTON, NORTH CAROLINA, A CORPORATION OF NORTH CAROLINA.

CALCULATING MACHINE.

Application filed June 26, 1919. Serial No. 306,888.

To all whom it may concern:

Be it known that I, JAMES F. MAYS, a citizen of the United States, residing at Lexington, in the county of Davidson and State of North Carolina, have invented new and useful Improvements in Calculating Machines, of which the following is a specification.

My present invention relates to improvements in calculating machines and more especially to those of the type embodying numeral dials which are advanced in response to the strokes of finger keys.

In such machines, it is essential, to secure accuracy, that the dial be advanced to its full extent in conformity with the value represented by the key struck, at each operation of such key. In practice, it has been found that in the operation of calculating machines as heretofore constructed, there is always present the possibility that a key, during the progress of a calculation, may not be pushed down or advanced to the limit of its stroke, this tendency being present particularly in calculating machines of the type wherein the downstrokes of the keys compress or tension springs and the springs drive the dials forward during the return strokes of the keys, the increasing tension of the springs during the down-strokes of the keys in such machines imposing a pronounced resistance upon the final portions of the key strokes, thus rendering the keys particularly subject to failure to complete their strokes. Failure of the operator to actuate a key to the full extent of its stroke is also likely to occur due to lack of uniformity in the resistance offered to the actuation of the different keys in the same machine, the keys representing the figures of higher value being usually more difficult to actuate as compared with the keys representing the figures of lower value. In any case, however, although the dial will be advanced nearly to the extent which it should be advanced, due to an incomplete key stroke, yet the result of the calculation will be inaccurate and so it has been customary heretofore, where such a failure has occurred, to reperform the calculation.

One of the primary objects of the present invention is to provide means to complete the advance of the dial in the event that the dial is not completely advanced by the key,

such means being relatively simple in its construction and operative with certainty and without imposing any appreciable resistance upon the operation of the key.

Another object of the present invention is to provide relatively simple and effective means for preventing overthrow or excess motion of the dial when advanced by the keys, such tendency being present especially when the dials are advanced by the keys representing the figures of the relatively higher values.

To these and other ends, the invention consists in certain improvements and combinations and arrangements of parts all as will be hereinafter more fully described, the features of novelty being pointed out particularly in the claims at the end of the specification.

In the accompanying drawings:—

Fig. 1 represents a vertical section taken longitudinally through a calculating machine constructed in accordance with the present invention.

Fig. 2 is a fragmentary section taken transversely of the machine showing two keys of adjacent columns, one key being in its actuated position and the other key in its normal or elevated position.

Fig. 3 represents a fragmentary section taken transversely through the machine showing the operative connections between the keys of two adjacent columns and the respective dial actuating shafts.

Fig. 4 is a detail view showing devices for two of the dials to prevent overthrow or excess motion in the advance thereof and also showing devices for such dials to complete the advance thereof should such advance be incomplete.

Fig. 5 is a detail view showing diagrammatically the operation of the device for completing the advance of the dial.

Fig. 6 represents an elevation of the structure shown in Fig. 4 as viewed from the right.

Fig. 7 is a detail perspective view showing the lower end of one of the key bars, the stop set thereby to limit the rotation of the dial actuating shaft and the member operative by the key to prevent overthrow or excess motion of the dial.

Similar parts are designated by the same reference characters in the several views.

The improvements provided by the present invention are applicable generally to calculating machines of the type employing numeral dials which are set by or under the control of keys. Certain features of the invention being especially applicable to such machines wherein the numeral dials are actuated by the keys irrespective of whether the dials are advanced directly by down strokes of the keys or whether the dials are advanced during the return strokes of the keys under the power of springs which are compressed during the preceding down-strokes of the keys. The preferred embodiment of the invention is shown in the drawings and will be hereinafter described as applied to a machine of the type in which the dials are advanced directly in response to the down-strokes of the keys. It is to be understood, however, that the invention is not restricted to the precise construction shown, as equivalent constructions are contemplated and will be included within the scope of the claims.

In the present instance the machine comprises a suitable casing 1 which is preferably of a generally rectangular construction, the top plate 2 having openings 3 and 4 therein through which the numerals on the primary registering dials and the quotient dials respectively may be observed and the top of the casing is also provided with slots or openings 5 through which the key bars operate. The keyboard shown is similar in its general construction and mode of operation to that shown and described in my prior Patent No. 1,301,073, granted April 15, 1919. It comprises briefly, a suitable number of columns of keys 6, there being nine keys in each column corresponding to the numerals 1 to 9 inclusive, the key at the extreme left in Fig. 1 corresponding to the numeral 1 and the keys to the right of said key corresponding successively to the numerals 2 to 9 inclusive. For convenience, I will designate the group of keys 6^a as corresponding to the numerals 1, 2 and 3, respectively, taken in their order from left to right; the group of keys 6^b as corresponding to the numerals 4, 5 and 6, respectively, reading in the same order; and the group of keys 6^c as corresponding to the numerals 7, 8 and 9 respectively, reading in the same order. Each key is provided with a key bar or stem 7 which extends downwardly through the respective slot or opening 5 in the top of the casing and through a guiding slot 8 formed in a flange 9, this flange constituting a part of an angle bar 10. One of these angle bars 10 is provided for each column of keys, it being supported rigidly within the casing by transverse plates or supports 11 and 12. A spring 13 is attached at one end to the top of the casing 65 and at its other end to a key bar and serves to return each key to its normal or elevated position and to hold the respective key in such position until operated. Each key bar for the keys of the group 6^b is provided with an operating projection 14. The key bars for the group of keys 6^a are provided with lateral projections 15 which normally rest upon the top of a key lever 16, this key lever being pivoted at 17 to a bracket 18, the latter being fixed within the casing. The operating projections 14 for the group of keys 6^b normally rest upon pins 19 which project from one side of a second key lever 20, the latter being pivoted to the bracket 18 at the point 21 and the key bars for the group of keys 6^c are provided with lateral projections 22 which normally rest upon the top of a third key lever 23, the latter being pivoted to the bracket 18 at the point 24. The key levers, 16, 20 and 23 for each column of keys rest upon a step or shoulder 25 which is formed on or carried by an actuating bar 26, the upper end 27 of the actuating bar being slidable vertically in a guide 28 fixed to the under side of the top of the casing and the lower end 29 of the actuating bar extending through a guiding slot formed in the flange 9 of the angle bar 10. Owing to the differential pivoting of the key levers 16, 20 and 23, and hence 90 the varying distances of the pivotal centers of these key levers from the step or shoulder 25 on the actuating bar 26, the actuating bar 26 will be actuated or depressed differentially or to varying extents as determined by the values represented by the different keys. The bar 26 and also the key levers 16, 20 and 23 are returned to their normal or elevated position and are held in such position by a tension spring 30, one end of which is attached to the bar 26 and the other end of which is attached to a pin 31 on the stationary guide 28. The differential movements of the bar 26 are transmitted to a dial actuating shaft 32 preferably through a crank 33 which is fixed to the shaft 32 and a link or connecting rod 34, one end of which is pivotally connected to the crank 33 and the other end of which is connected to the bar 26 by the pivot pin 35. One of these dial actuating shafts 32 is provided for each column of keys, and each shaft 32 is shown provided with means set by the different keys for limiting the rotation thereof as determined by the value 100 represented by the key which is struck, thus preventing overthrow or excess motion of the numeral dial which is actuated by this shaft. Such means corresponds in its general construction and mode of operation to that shown and described in my Patent No. 1,315,144, granted September 2, 1919. It consists briefly of a series of stop arms 36 fixed to the shaft 32, these stop arms 110 radiating from the shaft at graduated angles 120 to 130

to conform with the different angles through which the shaft rotates to advance the numeral dial to the proper extent to correspond with the value represented by 5 the different keys. This overthrow means also comprises stops 37 which are pivoted at 38 to the vertical flange 9 of the angle bar 10, the upper ends of the stops 37 being offset to overlie lugs 39 formed on the upper 10 edge of the angle bar 10 and the lower ends of the stops being bent laterally to form projections 40 arranged to be engaged and deflected by incline or cam surfaces 41 on the respective key bars. The stops 37 15 are normally held in a position to clear the stop arms 36 on the shaft 32 by their springs 42, but depression of any key will cause the incline 41 to deflect the projection 40 of the stop laterally, thus rotating the stop 20 on its pivot and bringing the upper end of the stop into the path of the appropriate stop arm 36 on the shaft 32. Each stop is thus set during the initial part of the down- 25 stroke of its respective key and the stop so set will arrest the rotation of the shaft 32 when this shaft has rotated to the proper degree corresponding to the value represented by the key which is struck. Each stop is automatically reset or restored to 30 inactive position by its spring when the respective key returns to its normal or elevated position. The shaft 32 is supported by bearings 43 and 44 mounted on the transverse supporting bars 45 and 12, ball 35 bearings being preferably used to minimize the resistance offered to the rotation of the shaft and particularly to minimize resistance to the return of the shaft to normal position after each actuation thereof. The 40 return rotation of the shaft 32 is effected by the spring 46, one end of which is fixed to the shaft and the other end of which is attached to a relatively fixed part, such as the cross member or support 11. 45 Each shaft 32 serves to actuate its respective registering or numeral dial 47 during the downstroke of a key in the respective column. As shown, a gear sector 48 is fixed on each shaft 32, such sector meshing with 50 a dial driving pinion 49, the dial driving pinion being connected to the respective dial through the medium of a lost motion connection 50 which is similar in its construction and mode of operation to the lost motion 55 connection shown and described in my prior Patent No. 1,323,894, granted October 18, 1919, the lost motion provided by this connection between the key operated shaft 32 and the respective dial occurring during the 60 initial part of the downstroke of the key, thus enabling the respective numeral dial to remain stationary while the shaft 32 rotates to an extent necessary to lock the carry mechanism for the different dials. 51 designates 65 one of the units of the carry mechanism, the

carry mechanism being of the construction shown and described in my prior Patent No. 1,309,535, granted July 8, 1919. Locking of the carry mechanism is effected, upon the initial part of the downstroke of any key, 70 by a cam 52 which is fixed to the forward end of each shaft 32 and cooperates with a roller 53 attached to a rock shaft 54, the rock shaft 54 having an arm 55 fixed thereon, the arm 55 being connected by a link 56 to the 75 common control member of the carry mechanism as fully shown and described in my said Patent No. 1,309,535. Each numeral dial 47 and corresponding carry mechanism unit is mounted on a dial shaft 57 and a 80 quotient dial 58 adapted to be used in operations of division is mounted preferably in alignment with the corresponding registering dial 47. The quotient mechanism shown corresponds substantially to that 85 shown and described in my prior Patent No. 1,309,536, granted July 8, 1919.

The present invention provides simple and effective means for preventing overthrow or excess motion of each numeral dial incident 90 to its advance under the action of a key stroke. As shown, a series of ten pins or projections 59 is carried in fixed relation on each dial shaft 57, these pins corresponding in number, spacing and position with the 95 numerals borne by the dial on the respective shaft. In order to facilitate the spacing of the mechanism within the machine, the pins or projections 59 are fixed directly on the forward side of the alternate dials while the 100 pins 59 for the remaining dials are fixed on the rear sides of disc 60 which are fixed on the remaining dial shafts, as will be understood clearly from Fig. 6. An overthrow check in the form of a bar 61 is provided 105 for each set of pins 59, each overthrow check being common to a column of keys. As shown in Fig. 4, each bar 61 is pivotally mounted at its lower end on a pin 62, the pin 62 being connected to a vertically movable slide 63 arranged at one side of a support 64. The support 64 is provided with a slot 65 to allow vertical movement of the pin 62 and a second pin 66 may be provided toward the lower end of the slide 63 and arranged to reciprocate in a slot 67 in the support 64 in order to aid in guiding the vertical movements of the slide 63. A spring 68 encircles the pin 62, one end of the spring 110 engaging a pin 69 on the bar 61 and the other end of the spring engaging a pin 70 on the slide 63, the spring acting to yieldingly hold the upper end of the bar 61 against a relatively fixed stop pin 71 mounted on the support 64, but permitting the upper end of the bar 61 to swing over and against a stop 72 in a manner that will be 115 hereinafter described. A spring 73 is attached at one end to the support 64 and at its other end to a part movable with the 120

125

130

slide 63, as for example, the pin 62, this spring acting to pull the slide 63 downwardly and to normally hold it in its lower position. The slide 63 rests on the forward 5 end of a lever 74, this lever being pivoted immediately above the bottom of the casing so as to rock vertically on a pivot pin 75. Normally, the spring 73 acting on the slide 63 will press and hold the forward end of 10 the lever 74 down against the bottom of the casing, the latter serving as a stop. The opposite or rear end 76 of the lever 74 underlies a projection 77 formed on the forward end of a bar 78, the latter being pivoted at 15 79 to the rear portion of the casing. One of these bars 78 is provided for each column of keys and each bar is formed with a set of lugs 80 which are located in line with respective key bars of the corresponding 20 column. The bar 78 is normally held in elevated position by the lever 74 under the action of the spring 73, the upper end of the bar or check 61 being then clear of the pins 59. Therefore while the overthrow check 25 is in the position described, the corresponding dial may be advanced without interference by the check. The lugs 80 on the bar 78, however, are so located with respect to the lower ends of the key bars that the final 30 portions of the down stroke of any key in the column will cause the lower end of the respective key bars to engage and depress the bar 78. In consequence the lever 74 will be rocked to reverse its position, its forward 35 end being elevated, thus pushing up the slide 63, as the result of which the bar 61 will be pushed upwardly bringing its upper end into a position between two adjacent pins 59 for the respective dial, the position 40 of the bar 61 at this moment being indicated by the dotted lines in Fig. 4. The final part of the advancing movement of the dial due to the continued descent of the actuated key will cause the pin 59 behind the bar 61 to 45 engage the bar 61 and swing it over against the stop 72 as indicated by the full lines at the left hand side of Fig. 4, the bar 61 then acting as a stop to prevent advance of the corresponding dial beyond the point to 50 which it should be advanced by the key which is struck. The initial part of the up or return stroke of the key causes the respective key bar to recede relatively to the bar 78 thus permitting this bar to rise and in 55 turn permit the lever 74 to return to its normal position. As a consequence the overthrow check or bar 61 descends and as soon as its upper end is withdrawn from the path of the pin 59 by which it was engaged, this 60 bar 61 will snap back against the stop 71 under the influence of its spring 68. The corresponding dial is then unlocked and it may be advanced by its carry mechanism upon completion of the return stroke of the 65 key, if such dial is due to receive a carry

from the dial of the next lower denomination, the operation of the carry mechanism being fully described in my Patent No. 1,309,535, hereinbefore referred to.

The present invention also provides means 70 for insuring complete advance of the dial at each operation thereof, or in other words, to complete the advance of a dial which has been only partially advanced through failure of the key to make a full stroke. Preferably 75 and as shown, the means for accomplishing this purpose cooperates with the pins 59 for the dial and it comprises a pawl 81 which is pivotally connected at 82 to a bar 83, the latter being pivoted to rock on a pin 84. A 80 tension spring 85 connects the pawl 81 and the bar 83, it acting to move the upper end of the pawl 81 toward or into engagement with the stop 72. A fixed stop 86 provides a 85 support on which the bar 83 may rest to limit the downward movement of said bar and the spring 87 acts on the bar 83 to yieldingly press the bar 83 downwardly or toward the stop 86. An arm 88 is fixed to the forward end of each shaft 32, the free end of 90 such arm being arranged in the path of the bar 83. Normally when all the keys of any column are elevated, the arm 88 will occupy the position shown on the right hand side of Fig. 4, the free end of the arm 88 then engaging the under side of the bar 83 and pressing the same upwardly, the upper end of the pawl 81 then bearing at the rear side of the appropriate pin 59. When a key in a 95 column is depressed, the corresponding shaft 100 32 is rotated in a direction which carries the arm 88 downwardly or away from the bar 83, the arm 88 being shown in such a position at the left hand side of Fig. 4. In consequence the bar 83 will descend until it rests 105 on the stop 86. During the advancing rotation of the corresponding dial incident to the down stroke of the key, the pins 59 will deflect the upper end of the pawl 81 and thus 110 pass the pawl freely. During the final portion of the return or upstroke of the key, the shaft 32 rotates the arm 88 back to the position shown at the right hand side of Fig. 4, the free end of the arm 88 engaging the under side of the bar 83 and pressing the 115 same upwardly carrying the pawl 81 upwardly to its normal position. If the dial has been completely advanced by a full stroke of the key, the pawl 81 will merely 120 ascend until it engages the under side of the pin 59 which is in line therewith, without, however, advancing the dial. In the event, however, that the dial has been advanced nearly but not completely to its full extent, the upper end of the pawl 81 will engage the 125 pin 59 in line therewith before the pawl 81 has completed its upstroke in consequence of which the pawl 81 will push ahead the pin 59 which it engages until the pawl 81 has completed its upstroke and in that manner 130

the advance movement of the dial is completed. The power necessary to actuate the pawl 81 to thus complete the advance of the dial is derived from the corresponding dial

5 actuating shaft 32 as such shaft returns to its initial position under the action of its spring 46 and also the spring 30, which acts upon the crank 33 attached to said shaft and hence certainty in the operation of the pawl 10 81 is insured. When the pawl 81 is in its normal position, as shown at the right hand side of Fig. 4, the corresponding dial is free to advance to receive a carry from the dial of next lower denomination, as the pin 15 59 which engages the side of the pawl will merely deflect the pawl as such pin assumes a position above the pawl.

It will be understood that the stroke of the pawl 81 is so determined that it will be sufficient to advance the dial through an angle corresponding to a fraction of the space between the numerals thereon. The pawl will then be able to complete the advance of the dial under ordinary circumstances where the 25 dial has not been fully or completely advanced by the key, for in such cases the failure to completely advance the dial is due to the fact that the key has been pushed nearly but not completely down to its limit 30 of stroke. The pawl 81 and its associated mechanism comprises therefore an auxiliary mechanism capable of completing the advance of the dial should the usual or key-operated mechanism fail to advance the dial 35 completely or to its full extent.

The overthrow check provided by the present invention is simple in its construction and it is certain in its action. It is positively set into operative position and as it is 40 interengaged between adjacent projections it cannot be thrown out of operative position by the movement of the dial. As the check yields laterally or advances with the dial, it 45 brings the dial to a gradual stop and hence rebound and shock are avoided.

What is claimed is:—

1. In a calculating machine, a dial, actuating means therefor, and means for preventing overthrow in the advance of the 50 dial comprising a series of projections movable with the dial, a member movable by said actuating means into a position in front of one of said projections during the advancing movement of the dial and capable 55 of advancing with such projections, and a stop for arresting such advancing movement of said member at a predetermined point.

2. In a calculating machine, a dial, actuating means therefor, and an overthrow 60 check for the dial comprising a series of projections fixed in relation to the dial, a member movable by the actuating means into a position ahead of one of said projections during the final part of the advancing movement of the dial, said member be-

ing yieldable to the advancing influence of such projection, and means for positively stopping the advance of said member at a predetermined point.

3. In a calculating machine, a dial, actuating means therefor, and an overthrow check for the dial comprising a series of projections connected to the dial to advance therewith, a pair of stops, and a member adapted to play laterally between said stops 75 and shiftable endwise by the actuating means into a position ahead of one of said projections.

4. In a calculating machine, a dial, actuating means therefor, and an overthrow 80 check for the dial comprising a series of projections arranged to advance with the dial, a pair of stops, and a member having means for yieldably holding it against one of said stops, said member being movable 85 by the actuating means into a position ahead of one of said projections whereby said member is advanced by the movement of the dial until arrested by the other of said stops.

5. In a calculating machine, a dial, actuating means therefor, and an overthrow 90 check for the dial comprising a series of projections arranged to advance with the dial, and a member reciprocatory by the actuating means into a position in front of 95 one of said projections and movable laterally whereby it may advance through its engagement with said projection, and means for limiting the extent of advance of said member.

6. In a calculating machine, a dial, actuating means therefor, and an overthrow check for the dial comprising a series of projections arranged to advance with the dial, a reciprocatory laterally-yieldable 105 member movable by the actuating means into a position in front of one of said projections, said member yielding laterally under the influence of said projection during the advance of the dial, and means for 110 positively arresting the laterally yielding movement of said member.

7. In a calculating machine, a dial, actuating keys, means operative by the keys for advancing the dial, and an overthrow check 115 for the dial comprising a series of projections arranged to advance with the dial, a longitudinally reciprocatory, laterally-yieldable member, means actuated by the final portion of a stroke of a key for moving said member into a position to be engaged and moved laterally by one of said projections during the final part of the advancing movement of the dial, and a relatively fixed stop for limiting such lateral 125 movement of said member, said member being retracted by the initial part of the return stroke of such key.

8. In a calculating machine, a plurality of dials, a key for advancing each dial, and 130

- auxiliary means individually operative in said series to advance the dial after the consequence of the actuation of each key for advancing of the dial by said dial advancing means has been terminated.
17. In a calculating machine, a dial, dial advancing means, a series of projections arranged to advance with the dial, and a reciprocatory member arranged to engage one of said projections and to move in the direction of advance of such projection to thereby advance the dial independently of the advance of the dial by said dial advancing means. 70
18. In a calculating machine, a dial, dial advancing means, a series of projections arranged to advance with the dial, and a reciprocatory laterally yieldable member operative to engage one of said projections and thus complete the advance of the dial should its advance by said dial advancing means be incomplete. 80
19. In a calculating machine, a dial, key-operated dial advancing means, a series of projections arranged to advance with the dial, and a pawl actuated by said dial advancing means and operative upon one of said projections to further advance the dial should the advance of the dial by the dial advancing means be incomplete. 85
20. In a calculating machine, a dial, key-operated dial advancing means, a series of projections arranged to advance with the dial, and a reciprocatory pawl actuated by said dial advancing means and operative upon one of said projections to complete the advance of the dial should its advance by the dial advancing means be incomplete. 90
21. In a calculating machine, a dial, key-operated dial advancing means, a series of projections arranged to advance with the dial, and a longitudinally reciprocatory laterally yieldable pawl reciprocated by said dial advancing means and operative to engage one of said projections and advance the dial should its advance by said dial advancing means be incomplete. 105
22. In a calculating machine, a dial, key-operated dial advancing means operative in one direction to advance the dial, a series of projections arranged to advance with the dial, and a pawl actuated by said dial advancing means during its return movement and operative on one of said projections to complete the advance of the dial should its advance by said dial advancing means be incomplete. 110
23. In a calculating machine, a dial, dial advancing means including a dial actuating shaft, a series of projections connected to the dial to move therewith, a longitudinally reciprocatory pawl adapted for endwise engagement with one of said projections, and an arm on said shaft operative to reciprocate said pawl in a direction to advance the dial. 120
24. In a calculating machine, a dial, dial advancing means, a series of projections con- 130
5. In a calculating machine, a plurality of dials, a key operative at each stroke thereof to advance its respective dial, and auxiliary means individually operative concurrently with the actuation of each key and capable of advancing the respective dial through the final portion of its advancing movement. 10
10. In a calculating machine, a dial, key-controlled means for advancing it, and auxiliary actuating means movable by said key controlled means in the direction of advance of the dial and capable of effecting the final portion of the advancing movement of the dial. 15
11. In a calculating machine, a set of 20 dials, keys operative at each actuation thereof to advance the respective dials, and auxiliary dial advancing means operative individually by the operation of the respective keys and movable in the direction of advance of the dials to complete such advance of the corresponding dials should their advance by the respective keys be incomplete. 25
12. In a calculating machine, a set of dials, keys each operative during a stroke 30 thereof in one direction to advance the respective dial, and auxiliary means operative individually during a stroke of its respective key in an opposite direction to complete the advance of the corresponding dial should its advance by its key be incomplete. 35
13. In a calculating machine, a set of dials, keys capable at each actuation thereof of completely advancing its respective 40 dial, and auxiliary means operative individually by the respective keys and capable of completing the advance of the dials should their advance by their respective keys be incomplete. 45
14. In a calculating machine, a dial, key-trolled actuating means including a member movable in one direction at each stroke of a key to advance the respective dial, and auxiliary dial-advancing means actuated by each reverse movement of said member to complete the advance of the dial should its advance by the first-mentioned actuating means be incomplete. 50
15. In a calculating machine, a dial, key-controlled actuating means including a shaft 55 rotatable in one direction to advance the respective dial at each stroke of a key, and auxiliary means actuated by return rotation of said shaft and capable of completing the advancing movement of the dial. 60
16. In a calculating machine, a dial, dial advancing means responsive to each stroke of a key, a series of projections arranged to advance with the dial, and a member operative to engage an appropriate projection of

- connected to advance with the dial, a longitudinally reciprocatory laterally yieldable pawl adapted for endwise engagement at one end with one of said projections, a bar pivotally attached to the other end of the pawl, and means actuated by the dial advancing means and operative upon said bar to reciprocate the pawl.
25. In a calculating machine, dials, dial actuating mechanism including a rock shaft, a column of keys for operating the dials, a reciprocatory actuating bar operative by such keys, a crank fixed to said shaft, and a rod operatively connecting said bar to said crank.
- 10 26. In a calculating machine, dials, dial actuating mechanism, a column of keys corresponding to the numerals 1 to 9 inclusive, a plurality of levers pivoted at different points, each of said levers being operative by a different group of said keys, and an actuating member common to and operative by any one of said levers, said actuating member being operative upon the dial actuating mechanism.
- 15 In testimony whereof I have hereunto set my hand in presence of two subscribing witnesses.
